UNITED STATES PATENT OFFICE.

FERDINAND WESEL, OF BROOKLYN, NEW YORK.

FOLIO-MORTISING MACHINE.

No. 813,756.

Specification of Letters Patent.

Patented Feb. 27, 1906.

Application filed January 14, 1905. Serial No. 241,138.

To all whom it may concern:

Be it known that I, FERDINAND WESEL, a citizen of the United States, residing at Brooklyn, in the county of Kings and State of New York, have invented new and useful Improvements in Folio-Mortising Machines, of which the following is a specification.

My invention pertains to metal-cutting machines, more particularly machines for cutting electrotypes and analogous plates; and it has for one of its objects to provide an accurate and expeditious folio-mortising machine—i. e., a machine calculated to correctly and quickly mortise an electrotype or like plate, so as to adapt the same to snugly receive folios or numbered blocks or interlocked blocks of other descriptions.

Another object of the invention is the provision of a duplex folio-mortising machine—that is to say, a machine at which two workmen acting independently of each other can accurately and expeditiously form mortises in electrotypes and other plates for the reception of folios and other blocks.

Other objects and advantages of the invention will be fully understood from the following description and claims when taken in connection with the accompanying drawings, forming part of this specification, in which—

Figure 1 is a front elevation of so much of the machine constituting the present and preferred embodiment of my invention as is necessary to illustrate the said invention. Fig. 2 is a top plan view of the machine with plates to be cut properly secured in position, one of the said plates being shown as presented to its complementary cutter and the other plate in the position it occupies precedent to being moved into engagement with its cutter.

Fig. 3 is an enlarged top plan view of one of the gages comprised in my improvements. Fig. 4 is a detail top plan view, on an enlarged scale, of one of the carriages of my novel machine and the parts appurtenant thereto, the said carriage being shown with an electrotype secured against casual movement thereon and being also shown in proper position relative to its complementary cutter. Fig. 5 is an enlarged detail top plan view illustrative of the adjustable plates, which are adapted to accommodate cutter-blades of various thicknesses between them. Fig. 6 is a detail view illustrative of one of the slides carried by the carriages, the working clamps on said slide, and the screw for feeding or moving the slide. Fig. 7 is an enlarged

vertical section taken in the plane indicated by the line 2 2 of Fig. 2 looking in the direction indicated by arrow, and Figs. 8, 9, 10, and 11 are views illustrative of the capabilities of the machine and hereinafter referred to in detail.

Similar letters designate corresponding parts in all of the views of the drawings, referring to which, A is the main frame of my novel machine, which may be of any construction compatible with the purposes of my invention, although I prefer the construction illustrated, which comprises a table B, as best shown in Figs. 1 and 2.

C is a shaft journaled in bearings *a* on the main frame and extending lengthwise of the machine in a vertical plane at one side of the table B and equipped with a pulley *b*, designed to be connected, through the medium of a band, (not shown,) with an electric or other suitable motor.

D D are rotary cutters fixed on the shaft C at points adjacent to the ends thereof and respectively made up by preference of a head *c* and blades *d*.

E E are casings containing the cutters D and having for their purpose to prevent flying cuttings from injuring or interfering with the work of the operatives, and F F are chutes communicating with and extending downwardly from the casings E and designed to convey cuttings to a box or other receptacle placed to receive the same. The casings E are preferably formed in part of transparent material (indicated by *e*) in order to enable the workmen to see the cutters which are designed to be rotated in the direction indicated by arrow, and said casings are provided in their fronts with horizontal slots or openings *f*, Fig. 7, in order to permit of the proper presentation of the plates to be cut (which are indicated by *g*) to the cutters.

G G are pairs of rails fixed with respect to the main frame A and disposed above the table B and at right angles to the shaft C, and H and I are carriages arranged on the said pairs of rails and designed to be moved by hand or otherwise toward and from the cutters D. The carriage H is provided with a dovetail slide *J* arranged therein, extending slightly above the upper side thereof and movable with respect thereto in the direction of the length of the machine or at right angles to the cutters. The said dovetail slide is provided with a depending nut *h*, movable lengthwise of the machine in a slot *i* of carriage H, and is

also provided wth a slot *k*, which extends from a point adjacent to its inner end to its outer end and has its lower portion enlarged, as best shown in Fig. 7. The nut *h* of the 5 slide *J* is designed to receive a feed-screw *K*, while the lower portion of the slot *k* of the slide is designed to receive enlargements *l* at the lower end of bolts *m*. These bolts *m* extend upwardly through the comparatively 10 narrow upper portion of the slot *k* and are provided above the slide with coiled springs *p*, cam-levers *r*, and clamps *s*, the said clamps being interposed between the cam-levers *s* and the springs and being provided at 15 their outer ends with depending portions *t*, arranged to bear against the upper side of the slide *J*, and at their inner ends with cushions or pads *u*, of leather or other suitable material, designed to bear on the electrotype 20 or other plate to be cut. By reason of the construction just described it will be observed that when the parts are in the relative positions shown in Fig. 6 a plate may be readily interposed between the padded ends of 25 the clamps *s* and the upper side of the slide *J*, also that when the cam-levers *r* are swung outwardly the plate will be securely fastened between the clamps and the slide *J*. It will further be observed that with the levers *r* in the position shown in Fig. 6 the bolts 30 *m* and the springs, clamps, and levers thereon may be moved in the direction of the length of the slide, so as to position the clamps to hold plates of various widths, also that a 35 plate may be adjusted with respect to carriage and cutter. The carriage *H* is further provided with brackets *L*, having depending arms *v*, which are vertically slotted for the passage of screws *w*, through the medium of 40 which they are connected to the front edge of the carriage in such manner as to permit of their vertical adjustment with respect thereto, this being advantageous in order to permit of the rearwardly-extending arms *x* 45 of the bracket being readily raised and lowered to accommodate plates of various thicknesses between the gage *M*, carried by said arms *x* of the brackets, and the upper side of the carriage *H*. Said carriage *H* is still further provided in its forward portion with a 50 notch *N*, disposed in alinement with the blades of the cutter *D* complementary to the carriage. The width of the said notch *N* is determined by plates *P P'*, which are connected 55 to the carriage by screws *y* taking through slots *z*, Fig. 5. The plate *P'* is provided with an arm *a'*, which laps the plate *P* at the rear thereof with a view of holding said plates in true alinement with their contiguous edges parallel, and 60 by virtue of the manner described of connecting the said plates *P P'* to the carriage *H* it will be observed that the width of the notch *N* at the top thereof may be readily increased or diminished to snugly receive cutter-blades of 65 various thicknesses. The gage *M*, which is

connected to the arms *x* of the brackets *L* by screws *b'* and is best shown in Fig. 3, is provided in its transverse center with a notch *c'*, which extends rearwardly from its forward edge, is alined with the before-described 70 notch *N* and terminates at its rear end in a longitudinal slot or **T**-head *d'*, a notch *e'*, which is alined with the notch *c'* and extends forwardly from the rear edge of the gage, and oblong openings or notches *f'*, which are disposed at opposite sides of the notches *c'* and *e'* and equidistant therefrom and extend forwardly from the rear edge of the gage parallel to said notches *c'* and *e'* and terminate at their inner ends in **T**-heads *g'*, disposed in 80 alinement with the **T**-head *d'*. The inner walls of the notches *f'* are beveled and graduated, as indicated by *h'*, the graduations being preferably appropriate to what is known in the printing and electrotyping art as the 85 "point system." The gage *M* is further provided with the inscriptions "line of cutter," which line is coincident with the outer walls of the **T**-heads *d'* and *g'* and graduations such as those designated "census" and 90 "quarto." It is obvious, however, that the said inscriptions and graduations may be omitted from the gage without involving a departure from the scope of my invention, also that graduations other than those designated "census" and "quarto" may be provided on the gage without affecting my said invention. The feed-screw *K* of the slide *J* is provided on its outer end with a hand-wheel *Q*, through the medium of which it 100 may be turned with facility, and the said hand-wheel is provided in turn with an indentation or other mark *k'*, which is designed in connection with a pointer *l'*, fixed with respect to the carriage *H*, to enable the 105 operator to accurately determine when he has made a complete revolution of the said feed-screw. In practice the feed-screw *K* is preferably so arranged that one complete revolution thereof will move the slide *J* and 110 the electrotype or other plate a distance corresponding to six points of what is known in the printing and electrotyping art as the "point system."

In the practical use of the carriage *H* and 115 its appurtenances, in connection with its complementary cutter *D*, an electrotype or analogous plate is secured on the slide *J* through the medium of the clamping means before described and best shown in Fig. 6, 120 and if the said plate is to be provided with a mortise in the center of its forward end it is positioned precedent to being clamped on the slide so that the opposite longitudinal lines of its type or other subject-matter rest 125 coincident with a certain couple of graduations at the rear edge of the gage *M*. For instance, if the electrotype is a quarto electrotype the opposite longitudinal edges of its type or subject-matter are placed so as 130

to register with the quarto graduations of the gage, and with this done it follows that when the mortise is cut in the end of the electrotype it will be in the center of said end. The 5 depth of the mortise to be formed in the end of the electrotype may be readily determined by the operator properly positioning the electrotype with reference to the graduated scales h' , and with this done the electrotype 10 is clamped on the slide J in the manner before described. With this done the carriage H is moved forwardly until its forward edge a^2 , Fig. 2, brings up against the portion a^3 of the main frame, when the cutter D will have 15 made the mortise desired. When the electrotype or other plate to be mortised is too narrow for the designated couples of graduations at the rear edge of the gage M to be used, the position of the electrotype may be 20 determined by alining its type or subject-matter with either of the walls of the notches f' , and in this way the said type or subject-matter may be accurately alined with the blades of the cutter. If the blades of the 25 cutter are of a thickness of, say, eighteen points and it is desired for the mortise to have a corresponding width, the plate is merely presented to the cutter in the manner described, and the result will be an 30 eighteen-point mortise, as shown by dotted lines in Fig. 8. If, however, a mortise of, say, twenty-four-points wide is desired, the plate is fed to the cutter and the feed-screw K is turned through one complete revolution, when, as will be readily appreciated, 35 the plate will be fed at right angles to the cutter, and the result will be a mortise such as shown by dotted lines in Fig. 9. The said mortising of the plates is for the accurate 40 and expeditious removal of folios such as shown in full lines in the lower portions of Figs. 8 and 9 and the substitution therefor of folios bearing other numbers. The said folios are placed and soldered in the mortises, 45 and the result is an electrotype or analogous plate quite as perfect and durable as the original one. The cut to be made by the cutter in the end of the electrotype or other plate is not limited to the twenty-four points 50 mentioned, but, on the other hand, is only limited by the extent to which the electrotype may be fed through the medium of the screw K. For instance, if the cut is to have a width of thirty-six points the feed-screw K 55 is turned through three complete revolutions, this giving a feed of eighteen points, which in addition to the eighteen points of the cutter-blades will afford the cut of the width desired. The mortise shown in Fig. 11 is 60 formed in the same way as that shown in Fig. 9, but is of a less width than the latter. The mortise shown in Fig. 10, however, is formed by determining the position of the electrotype or other plate through the medium of 65 the left walls of the notches c' and e' of gage

M—i. e., by registering the line of type at the left of the electrotype with the left wall of the said notches. When the mortise is to be formed adjacent to the forward right corner of the electrotype, the line of type at the 70 right of the electrotype is registered with the right wall of the notches c' and e' .

From the foregoing it will be readily appreciated that the operator at the right of my novel machine is enabled, through the 75 medium of my improvements, to very quickly and accurately mortise an electrotype or analogous plate and determine the position and extent of the mortise, and hence a large number of the plates may be mortised in a 80 short period by a single workman, which is a desideratum.

In order that the operator at the right of my novel machine may utilize a block to determine the width of a mortise in a plate in 85 which the block is to be placed and secured, I provide the attachment T. (Shown in Fig. 4 of the drawings.) The said attachment comprises a slide-block shaped in conformity to and arranged in the groove of the slide J and 90 having a transverse groove a^5 and also having a threaded post b^6 rising from the bottom of said groove, a nut c^5 , mounted on the threaded post, and a bracket-arm d^5 , having a bifurcated portion straddling the threaded 95 post and arranged in the groove a^5 of the slide-block, whereby it is held against lateral wobbling or play and interposed or clamped between the nut and the slide-block, and also having a depressed portion e^5 , provided in its 100 longitudinal center with a raised rib f^5 . It will be observed that when a block is placed on the depressed portion of the bracket-arm d^5 and is interposed between the rib f^5 and the adjacent edge of the carriage H and the 105 nut c^5 is tightened, and the block removed the rib f^5 will, when it brings up against the 110 said edge of the carriage, stop the movement of the slide toward the right, and thereby assure the production in a plate of a mortise corresponding in width to and adapted to snugly receive the said block.

The carriage I at the left of the machine is similar to the carriage H in that it is equipped with brackets L, a gage M, and plate-clamping means like those of said carriage H, and also in that it is adapted to be moved forwardly and rearwardly, so as to carry a plate to be mortised into and out of engagement with its complementary cutter D. Said carriage I, however, differs from the carriage H in that its bar J' is not a slide-bar, but is fixed with respect to it, and hence has no longitudinal movement. From this it follows that the carriage I and its appurtenances are 115 designed for the class of work in which the width of the mortises is determined by the width or thickness of the blades of the cutter. It is obvious, however, that the said carriage I might be equipped with all of the appurte- 120 125 130

nances common to the carriage H without involving a departure from the scope of my invention.

As will be gathered from the foregoing, 5 my invention contemplates the operation of the carriage H and its appurtenances by one workman and the operation of the carriage I and its appurtenances by another workman, and also contemplates the employment of 10 the portion of the table B intermediate the carriages H and I as a support for the plates. In order to enable either workman to cut off electric current from the electric motor, and thereby stop the shaft C when necessity demands, 15 I provide the switches M at the front of the main frame and below the carriages H and I.

I have entered into a detailed description 20 of the construction and relative arrangement 25 of the parts embraced in the present and preferred embodiment of my invention in order to impart a full, clear, and exact understanding of the said embodiment. I do not desire, however, to be understood as confining myself to such specific construction and relative arrangement of parts, as such changes or modifications may be made in practice as fairly fall within the scope of my invention 30 as claimed.

Having described my invention, what I 35 claim, and desire to secure by Letters Patent, is—

1. In a folio-mortising machine, the combination of a vertically-movable cutter, a carriage 40 movable horizontally toward and from the edge of the cutter and having a notch in its forward edge to receive the edge of the cutter, and a gage carried by and resting above the carriage and provided with means 45 for determining the position of a plate relative to said notch of the carriage.

2. In a folio-mortising machine, the combination of a vertically-movable cutter, a carriage 50 movable horizontally toward and from the edge of the cutter and having a notch in its forward edge to receive the edge of the cutter, and a gage carried by and resting above the carriage and having a graduated scale extending in the same direction as the 55 notch in the carriage.

3. In a folio-mortising machine, the combination of a vertically-movable cutter, a carriage 60 movable horizontally toward and from the edge of the cutter and having a notch in its forward edge to receive the edge of the cutter, and a gage carried by and resting above the carriage and having oblong openings 65 extending parallel to the notch in the carriage and arranged at opposite sides of and equidistant from the plane of said notch and also having a graduated scale extending in the same direction as the notch in the carriage.

4. In a folio-mortising machine, the combination of a vertically-movable cutter, a carriage

movable horizontally toward and from the edge of the cutter and having a notch in its forward edge to receive the edge of the cutter, a gage carried by and resting above the carriage and having a notch in its forward edge registered with the notch in the carriage and also having a slot at the rear end of its notch extending at right angles to said notch, and plate-holding means movable on the carriage at a right angle to the direction of movement of the cutter and the direction of movement of the carriage. 70 75

5. In a folio-mortising machine, the combination of a vertically-movable cutter, a carriage 80 movable horizontally toward and from the edge of the cutter and having a notch in its forward edge to receive the edge of the cutter, a gage on the carriage provided with means for determining the position of a plate 85 relative to said notch, plate-holding means movable on the carriage at a right angle to the direction of movement of the cutter and the direction of movement of the carriage, means for moving the plate-holding means with respect to the carriage, and means for 90 determining the extent of movement of the plate-holding means with respect to the carriage.

6. In a folio-mortising machine, the combination of a vertically-movable cutter, a carriage 95 movable horizontally toward and from the edge of the cutter and having a notch in its forward edge to receive the edge of the cutter, a gage on the carriage provided with means for determining the position of a plate 100 relative to said notch, plate-holding means movable on the carriage at a right angle to the direction of movement of the cutter and the direction of movement of the carriage, and having a depending nut, a screw-bearing 105 in the carriage and engaging the nut of the plate-holding means and having a wheel provided with a mark, and a pointer on the carriage arranged to coöperate with said mark on the wheel. 110

7. In a folio-mortising machine, the combination of a vertically-movable cutter, a carriage 115 movable toward and from the cutter and having a notch in its forward edge, and plates for determining the width of the said notch; the said plates being adjustably connected to the carriage, and one of the same having an arm lapping the other at the back thereof.

8. In a folio-mortising machine, the combination of a vertically-movable cutter, a carriage 120 movable horizontally toward and from the cutter, a plate-carrying slide movable on the carriage at a right angle to the direction of movement thereof, means for moving said slide with respect to the carriage, a bracket-arm adjustably connected to the slide, at one side of the carriage, and having a rib and also having means, at one side of the rib, for supporting a block interposed be- 125 130

tween the rib and the adjacent edge of the carriage.

9. In a folio-mortising machine, the combination of a vertically-movable cutter, a carriage movable horizontally toward and from the edge of the cutter and having a notch in its forward edge arranged to receive the edge of the cutter, a gage connected with the forward edge of the carriage and overhanging said carriage, and provided with means for determining the position of a plate relative to said notch of the carriage and plate-holding means movable on the carriage at a right angle to the direction of movement thereof.

10. In a folio-mortising machine, the combination of a cutter, a carriage movable toward and from the cutter, and having a groove extending at an angle to its direction of movement, bolts having enlargements disposed in said groove, clamps mounted on the bolts, springs supporting the clamps, and cam-levers mounted on the bolts, above the springs.

25 11. In a folio-mortising machine, the combination of a cutter, a carriage movable toward and from the cutter, a slide movable in the carriage at an angle to the direction of movement thereof and having a longitudinal groove, and also having a depending nut, bolts having enlargements disposed in said groove of the slide, clamps mounted on the bolts, springs supporting the clamps, cam-levers mounted on the bolts, above the springs, 35 and a feed-screw carried by the carriage and bearing in the nut of the slide.

12. In a folio-mortising machine, the combination of a cutter, a carriage movable toward and from the cutter, plate-holding means on the carriage, and a gage carried by the carriage and having a notch in its forward edge to receive the cutter and notches in its rear edge parallel to the first-mentioned

notch, and also having a longitudinal slot one longitudinal wall of which fixes the line of 45 cut, and means whereby the depth of the cut in the plate may be determined.

13. In a folio-mortising machine, the combination of a cutter, a carriage movable toward and from the cutter, plate-holding 50 means on the carriage, and a gage carried by the carriage and having a notch in its forward edge to receive the cutter and notches in its rear edge parallel to the first-mentioned notch and also having a longitudinal slot one 55 wall of which fixes the line of cut, and a graduated scale parallel to one of the last-mentioned notches whereby the depth of the cut in the plate may be determined.

14. A gage for use on folio-mortising machines having a notch in its forward edge to receive a cutter, and notches in its rear edge parallel to the first-mentioned notch, and also having a slot one wall of which is to fix the line of cut, and a graduated scale parallel 60 to the last-mentioned notches whereby the depth of the cut in a plate may be determined.

15. In a folio-mortising machine, the combination of a cutter, an abutment, a carriage 70 movable toward and from the cutter and arranged to bring up, on its movement toward the cutter, against the abutment, and a gage carried by the carriage and having a notch to receive the cutter, and also having a longitudinal slot the rear wall of which is coincident with the line of cut, and further having means whereby the depth of the cut in a plate may be determined.

In testimony whereof I have hereunto set 80 my hand in presence of two subscribing witnesses.

FERDINAND WESEL.

Witnesses:

EMIL STEAHANY,
J. LEWIS NATTER.
